UNITED STATES PATENT OFFICE.

CLEMENT F. STREET AND NATHAN M. LOWER, OF SCHENECTADY, NEW YORK, ASSIGNEES TO THE LOCOMOTIVE STOKER COMPANY, OF WILMERDING, PENNSYLVANIA, A CORPORATION OF PENNSYLVANIA.

MECHANICAL STOKER.

1,195,528.

Specification of Letters Patent. Patented Aug. 22, 1916.

Application filed October 2, 1911. Serial No. 652,462.

To all whom it may concern:

Be it known that we, CLEMENT F. STREET and NATHAN M. LOWER, both citizens of the United States, residing at Schenectady, in the county of Schenectady and State of New York, have invented certain new and useful Improvements in Mechanical Stokers, of which the following is a specification.

This invention relates to mechanical stokers of the so-called scatter type, in which lump fuel is distributed over the grate of the fire box by means of jets or blasts of fluid pressure through suitable distributor nozzles directed over different portions of the grate area, as described in the prior application of C. F. Street Serial No. 565,579, filed June 7, 1910.

The object of the present invention is to provide improved means for regulating the amount and character of fuel delivered to the several distributor units in order that the fire may be properly controlled and all of the fuel be efficiently consumed.

In the accompanying drawing, Figure 1 is a front elevation of a boiler furnace with our improved system of fuel discharge pipes and regulating devices for delivering the fuel to the distributor nozzles, portions of the discharge and conveyer pipes being broken away; Fig. 2, a transverse section of the discharge pipe and screen taken on the line α α of Fig. 1; Fig. 3, a similar transverse section taken on the line y y of Fig. 1; Fig. 4, a longitudinal section of the separating screen; and Fig. 5, a transverse section thereof.

As shown and described in the prior application above referred to, the apparatus is applied to the boiler furnace of a locomotive and comprises, generally, a fuel elevator in the form of a continuous conveyer, 13, operating in tubes, 12, for discharging fuel into a hopper over the furnace door, 6, from which hopper, fuel conduits lead to the respective distributor units which pass through the walls of the furnace at different points for distributing the fuel over different portions or zones of the grate area, there being two side distributor units and one intermediate or centrally located distributor.

It is found to be desirable to supply most of the fine or smaller pieces or lumps of fuel to the intermediate or middle portion of the grate, and the larger lumps along the outer

side portions of the same, and our present invention is designed to regulate the distribution of the fuel in this manner.

According to the particular form of apparatus shown in the present drawing, the hopper of the prior device is dispensed with and the delivery pipes or conduits, 19^a and 19^b, leading to the respective side distributor units, 19 and 19^a, and the delivery conduit, 20^a, leading to the intermediate distributor, 20, all communicate with the transverse pipe section, 18, of the elevator casing, 12, through which the endless bucket conveyer, 13, passes in raising the fuel from a lower receptacle, not shown.

For the purpose of regulating the character as to size and the relative proportion of the amount of fuel which shall be delivered to the intermediate conduit, 20^a, which is the first in order to receive fuel, an adjustable assorting riddle or screen, 51, is provided at the opening from the supply pipe or casing, 18, to said pipe, 20^a, so that the small pieces or fine part of the fuel may be delivered to the intermediate distributor, while the larger lumps are carried along over the screen to the discharge opening leading to the conduits of the side distributor units. The screen, 51, is preferably in the form of a hollow perforated cylinder rotatably mounted in the pipe, 18, and provided upon its circumference with a plurality of sets of perforations of different sizes, as shown more fully in Figs. 4 and 5. For the purpose of rotating the screen and thereby adjust the same so that the several sets of perforations may be brought into position for use, a pivoted lever, 53, may be provided having a spring ratchet arm, 53^a, engaging notches in the cylindrical screen, 51, as shown more clearly in Fig. 2. By this means the screen may be rotated to any position in which the desired set of perforations is located at the bottom of the cylinder over the inlet opening to the intermediate conduit, 20^a, and beneath the buckets of the conveyer which passes through the cylindrical screen.

If there should be a large quantity of fine particles or dust in the fuel, the division of the screen having the small perforations may be rotated to the position beneath the conveyer buckets, but if it is then found that there is not a sufficient quantity of fuel delivered to the center distributor,

the screen may be rotated until a division having larger perforations is brought into position for use, thereby affording a means for obtaining a fine graduation of the amount of fine fuel delivered to the intermediate or center distributor.

As the conveyer carries the larger pieces or lumps of fuel over or through the cylindrical screen, it reaches the opening communicating with the conduits 19^a and 19^b, which are located side by side transversely of said supply pipe or casing, 18, and for the purpose of varying the relative amount of fuel which may be delivered to said side 10 distributors respectively, a deflector, 47, may be pivoted between these pipe connections and be adjusted from one side to the other by means of a handle, 50, extending out through the casing, and having means 15 for securing the same in any desired position, as shown more fully in Fig. 3. The deflector may usually be vertical to give substantially equal quantities of fuel to each of the side distributors, but if at any 20 time, it is desired to divert a larger amount to one side than to the other, the deflector may be readily adjusted in the desired position.

As the pipe section, 18, of the elevator 25 casing extends in a direction transverse to the furnace and to the railway track, and the deflector is similarly alined, the tendency of the lateral or rocking movement of the locomotive when running, to cause irregular or unequal amounts of fuel to be 30 fed to one conduit or the other, is entirely eliminated, and the deflector, when adjusted, in any given position, operates to divert the desired proportions of fuel to the respective conduits, regardless of the transverse swaying or lurching of the locomotive.

The distributors may be provided with the fluid pressure nozzle connections, 28, 45 and the air inlets, 27, as shown and described in the prior application above referred to, and while we have herein illustrated our improvements in connection with two side distributors and one center distributor, it will be evident that a different number may be employed if preferred, and also that more than one intermediate distributor may be used if desired.

Having now described our invention, what 50 we claim as new, and desire to secure by Letters Patent, is:

1. In a mechanical stoker, the combination of a fuel supply, a plurality of separate conduits leading to different portions 60 of the furnace, means for assorting the fuel as to size, and means for feeding the smaller pieces to one conduit of the furnace and the larger pieces to another conduit.

2. In a mechanical stoker, the combination of a plurality of separate distributor

communicating at different points transversely of the furnace, conduits leading to the several distributors, a source of fuel supply delivering to the conduits, and means for assorting the fuel as to size as 70 delivered to the respective conduits.

3. In a mechanical stoker, the combination of a delivery pipe, a conveyer mounted to travel in the pipe, a plurality of distributors, conduits leading downwardly 75 from the pipe to the distributors, their receiving ends being arranged longitudinally as to the pipe, and a reticulated screen crossing the receiving end of the conduit first in order, the other conduits not having 80 similar screens, whereby fuel passed through the pipe is delivered to the conduits in assorted sizes.

4. In a mechanical stoker, the combination of a delivery pipe, a conveyer mounted 85 to travel in the pipe, conduits leading laterally from the pipe and arranged longitudinally thereof, and a rotatable cylindrical screen, having a plurality of differentiated sections, housed within the pipe and 90 covering the receiving end of the conduit first in order.

5. In a mechanical stoker, the combination of a plurality of conduits for delivering fuel to different portions of the furnace, 95 a conveyer casing for supplying fuel to said conduits successively, and a perforated screen located over the receiving end of the first conduit for assorting the fuel as to size as delivered to the successive conduits, the other conduits not having similar screens.

6. In a mechanical stoker, the combination with a plurality of distributors for distributing the fuel over different portions of the grate area, of separate conduits for delivering fuel to said distributors, a conveyer casing for supplying fuel to said conduits successively, and an adjustable perforated screen located over the receiving end of the first conduit only, whereby the fuel delivered to said conduits is assorted as to size.

7. In a mechanical stoker, the combination with a plurality of side distributors and an intermediate distributor for distributing the fuel over different portions of the grate area, of separate conduits for delivering fuel to said distributors, a conveyer casing for supplying fuel to said conduits, the conduit for the intermediate distributor being connected to said casing in advance of the other conduits, and a perforated screen located over the receiving end of said first connected conduit only for assorting the fuel as to size and feeding the smaller pieces to the intermediate distributor.

8. In a mechanical stoker, the combination with a plurality of distributors for distributing fuel over different portions of the

- grate area, and separate conduits for delivering fuel to said distributers, of a supply pipe or casing communicating with the respective delivery conduits successively, 5 and a cylindrical screen having perforations of different sizes, rotatably mounted in said casing over the receiving end of the first conduit, the fuel being delivered in assorted sizes to said conduits.
- 10 9. In a mechanical stoker, the combination with a plurality of side distributers, and an intermediate distributer for distributing fuel over different portions of the grate area, of separate conduits for delivering fuel to said distributers, a discharge pipe or conduit communicating with the respective delivery conduits, a perforated screen for regulating the supply of fuel from the discharge pipe to the delivery conduit of the intermediate distributer, and an adjustable deflector for varying the amount of fuel delivered from the discharge pipe to the respective side distributers.
- 15 10. In a mechanical stoker, the combination with a plurality of side distributers and an intermediate distributer for distributing the fuel over different portions of the grate area, of separate conduits for delivering fuel to said distributers, an adjustable 20 perforated screen for regulating the character and amount of fuel delivered to an intermediate conduit, and an adjustable de- flector for varying the amount of fuel delivered to the respective side distributers.
- 25 11. In a mechanical stoker for locomotives, the combination of a plurality of fuel distributers, a delivery pipe arranged transversely of the locomotive, conduits leading laterally from the pipe to the several distributers, and an adjustable deflector plate 30 separating the receiving ends of a pair of the conduits and disposed parallel to the axis of the pipe.
- 35 12. In a mechanical stoker for locomotives, the combination of a plurality of conduits for delivering fuel to different portions of the furnace, a supply pipe arranged transversely of the locomotive and communicating with said conduits, said conduits having their inlet openings located 40 side by side transversely of said supply pipe, and an adjustable deflector mounted between said openings and parallel with the supply pipe for regulating the amount of fuel delivered to the respective conduits. 50
